UNITED STATES PATENT OFFICE.

GEORGE HAZELTON, OF PARIS, FRANCE.

BIPOD.

Application filed August 24, 1923. Serial No. 659,211.

To all whom it may concern:

Be it known that I, GEORGE HAZELTON, a subject of the King of Great Britain and Ireland, and residing at 7, Rue Georges 5 Ville, Paris, 16^e, France, have invented a certain new and useful Bipod, of which the following is a specification.

The devices which have been employed hitherto for supporting the front ends of 10 machine guns during firing, and which are so constructed as to be capable of occupying a folded position when they are not in use, and of being moved into the desired position for firing purposes, are generally fairly difficult to handle, that is to say, the said supports are not adapted to be brought into the desired position in a simple and rapid manner.

The present invention has for its object to 20 provide a folding trestle to serve as a front support for machine guns and the like firearms, which is without such drawbacks. This improved folding trestle is so designed that it can be folded in a compact form underneath the barrel of the gun, and it is so constructed that it can be brought easily and quickly into the position required for firing purposes.

This folding trestle comprises substantially 30 two cranked or bent legs mounted in a cylindrical plug revoluble in the head of the trestle in which the gun can swivel, the whole being arranged in such a manner that the legs are capable of being rotated in the cylindrical plug only when the latter has 35 been brought into a determined position relative to the trestle head wherein angular rotation of the said legs in one direction causes these to come together, and brings them into a position parallel to and underneath the gun barrel, while locking the plug in the trestle head. Angular rotation of the legs in the reverse direction causes the legs to move apart while unlocking the plug and 45 allowing the legs to be turned down to the ground.

To enable this invention to be clearly understood, I shall now proceed to describe, with reference to the accompanying drawings, but by way of example only, a constructional form of the improved trestle according to this invention.

Figure 1 is an elevation showing the apparatus folded for transport, and designed 55 for use with a machine gun.

Figure 2 is a corresponding plan.

Figures 3, 4 and 5 are respectively a plan, an elevation and a rear end view of the piece in which revolve the pivot of the gun and the cylindrical plug carrying the legs. 60

Figure 6 is a detail view of the said cylindrical plug.

Figure 7 is a section taken through the trestle head.

Figures 8 and 9 are respectively a front 65 elevation and a side elevation of the upper end of a leg.

Figure 10 is a section on the line A—A of Figure 1, viewed in the direction of the arrow X. 70

Figures 11 and 12 are an elevation and a plan of the apparatus in position during firing.

As shown in the accompanying drawings 75 the improved folding trestle comprises a collar 1, in which works the pivot pin of the machine gun. The said collar and pivot pin are kept together by a pin 2 passed through the collar its middle part projecting into an internal circular groove 3 formed in the pivot pin (Figure 1), thus permitting the gun to be swivelled relative to the collar.

This collar is integral with a second cylindrical collar 4, whose longitudinal axis is at right angles to the axis of collar 1. The 85 collar 4 has in each of its flat ends a semi-cylindrical notch 5 whose axis is situated in the plane of the respective end surface, and is inclined relatively to the plane end surfaces of the collar 1. 90

A cylindrical plug 6, mounted so as to be rotatable in the collar 4, is pierced by two holes 7 whose diameter is equal to the diameter of the notches 5 of collar 4, and whose parallel axes intersect the axis of the 95 plug at right angles, (Figures 6 and 7). These axes are situated in the planes of the bases of the collar 4 (Figure 7), and the holes 7 can be brought into the prolongation of the notches 5 by rotation of the plug 100 6. This latter is, further, pierced in the centre of each of its flat ends by a screw-threaded hole 8 adapted to receive a screw 9 which, extending into each hole 7 of the plug, engages in a circular groove 10 provided close to the upper end of each of the legs 11, and prevents these latter from having any longitudinal movement while allowing them to rotate.

In order to allow the plug 6 in which 110 the upper ends of the legs are mounted to rotate with the legs in the collar 4, the said

ends are of circular cross-section and formed with notches 13 and 14 having a depth equal to half the diameter of the said ends. The flat surfaces 15 of these notches, extending 5 through the axis of the legs, are cut away in such a manner as to come in contact with the flat ends of the collar 4 during the rotation of the plug 6 in the interior of the said collar, whereas the lower ends of the legs 10 11 diverge at the maximum angle allowed by the rotation of the upper ends of the legs in the holes 7. The surfaces 16 of the notches 13 and 14 at right angles to the surface 15 are cut to cylindrical shape and 15 they form a continuation of the outer surface of the plug 6, when the flat surfaces 15 are in contact with the bases of the collar 4 as shown in Figure 7.

The lower ends of the legs 11 terminate 20 in sharp points and carry plates 17 that prevent them from penetrating too deeply into the ground. These plates have notches 19 which are adapted to engage the machine gun barrel 18 in the position of transport 25 shown in Figures 1 and 2, in which the legs are held by a sliding ring 20.

The operation of the improved trestle is as follows:—

In its folded position shown in Figures 1 30 and 2, the plug 6 cannot turn in the collar 4 owing to the engagement in the fixed notches 5 of one half of the semi-cylindrical parts lying at the upper part of the legs 11, by the notches 13 and 14. The legs being 35 close together in this position, are prevented by a ring 20 from suffering any accidental displacements. The apparatus is now locked in its position of minimum bulk.

In order to bring the legs into position 40 for firing, the ring 20 is shifted along the legs 11 in the direction of the arrow X (Figures 1 and 2) and the legs 11 are simultaneously rotated through one quarter of a revolution around their longitudinal axis 45 in the direction of the arrows Y (Figure 2). Since these legs are bent they will move away from each other as shown in Figures 7 and 11. In this angular rotational motion the semicircular portions of the legs 50 situated opposite notches 13 and 14 are brought to the outside of the collar 4, and the flat surfaces 15 become situated in the plane of the ends of the said collar as is clearly shown in Figures 7 and 12.

55 The plug 6 is now free and can be rotated together with the legs which it carries about

the common axis of the said plug 6 and collar 4, in order to bring the apparatus into the open position shown in Figures 11 and 12, or in any other position around the said 60 axis.

The legs 11 cannot then be brought together, because the flat surfaces 15 of each leg are in contact with the flat base of the collar 4 and oppose the rotation of the legs 65 11 in the holes 7 of the plug 6, as is clearly shown in Figures 7, 11 and 12. In this position, the lower horizontal edge of the notch 14 of each leg is in contact with a flat portion 21 (Figures 1 and 4) formed on the lower face of the collar 4 in such a manner that the legs are not able to fold down in a forward direction.

In order to return the trestle into the position shown in Figure 1, the legs 11 must first be raised towards the gun barrel 18, the plug 6 thus being turned in the collar 4 until the holes 7 in the said plug have come opposite the fixed notches 5. It is then sufficient to turn the legs 11 around their longitudinal axis for the purpose of bringing them together and engaging again the half of their upper semi-cylindrical portions in the fixed notches 5. The trestle will then be locked as above stated.

It is to be understood that the construction, arrangement and details as hereinbefore described, are given solely by way of example and that shapes, materials and dimensions of the various constituent parts 90 may be modified without thereby departing from the nature of the invention.

Having now described my invention, what I claim as new and desire to secure by Letters Patent is:—

A folding front support for machine guns and the like including a head adapted to be secured to the gun, a cylindrical member rotatably mounted within said head, two cranked legs rotatably mounted near their ends within said cylindrical member, means enabling said legs to be folded to occupy a position parallel to the gun barrel, means in connection with said legs serving when the latter occupy the above-mentioned position to lock the cylindrical member to the head, said locking means being releasable by rotation of the legs about their longitudinal axes.

In testimony whereof I have signed my 110 name to this specification.

GEORGE HAZELTON.
